LOOSE-LEAF POST BINDER

Frank Stanley Schade, Holyoke, Mass., assignor
to National Blank Book Company, Holyoke,
Mass., a corporation of Massachusetts

Application January 8, 1947, Serial No. 720,741

4 Claims. (Cl. 129—24)

1

This invention relates to improvements in loose leaf post binders and particularly to the mechanism for mounting, fastening and releasing the posts in the back of a binder case.

The purpose of the invention is to make a better structure at lower cost than competitive binders now on the market. The way this is done will need to be explained in detail. After the detail is understood the invention will be seen in the combination of parts.

Referring to the drawings:

Fig. 1 indicates a binder case consisting of a back portion and two hinged covers before the loose leaf binder mechanism is mounted on the back portion;

Fig. 2 is a plan view of post binder mechanism in assembled condition;

Fig. 3 is a side view of the mechanism in Fig. 2;

Fig. 4 is a bottom view;

Fig. 5 is a plan view of a one piece channel member;

Fig. 6 is an end view of the member in Fig. 5 as indicated;

Fig. 7 is a plan view of a companion one piece channel member;

Fig. 8 is an end view of the member shown in Fig. 7 as indicated;

Fig. 9 is a side view of the member shown in Figs. 7 and 8 viewed as indicated by arrows in Fig. 8;

Fig. 10 is a section on line 10—10 of Fig. 8; and

Figs. 11, 12 and 13 are plan, side and bottom views respectively of a form of post preferred for use in the mechanism.

In Fig. 1 a typical binder case having covers 1 and 2 separated by a back portion 3 is shown with the covers in open position, but without loose leaf binder mechanism attached. Such mechanism is fastened to the back portion 3, usually by rivets. An example of my improved loose leaf binder mechanism construction, in which my preferred form of binder post mounting is incorporated, is shown in Figs. 2, 3 and 4 in completely assembled form ready to be attached to a binder case back. This mounting consists of a U-shaped channel member 4 in which a second U-shaped channel member 5 is cradled. The channel member 5 is adapted to slide back and forth from a central locking position within a guideway provided by upturned side walls 6 of channel member 4 against frictional restraint and within certain limits, as will be explained later. The side walls 6 are folded over, as shown in Fig. 6, to form a track to receive side walls 7 of channel member 5. In addition notches 8 are cut in side walls 6 to receive socket portions 9 and 10 of loose leaf sheet retaining post members 11, said members 11 normally bridging the U-shaped channel members, as shown in Fig. 2, while retaining a stack of looseleaf sheets. Prongs 12 and 13 formed in side

2

walls 7 of channel member 5, see Figs. 9 and 10, are adapted to enter the sockets 9 and 10, Fig. 12, to lock the sheet carrying post members 11 in sheet retaining position, or to be withdrawn to one side or the other to a post member releasing position when the channel member 5 is slid within guide channel 4. It will be noted, as shown in Figs. 9 and 10 and as viewed in those figures, prongs 12 are so formed that they point to the left, while prongs 13 point to the right. Thus, if the channel member 5 is centrally disposed within channel member 4, as in Fig. 2, both sets of prongs 12 and 13 extend through their respective socket portions of post members 11 locking said post members in sheet retaining position. From this central position, and considering Figs. 2, 9 and 10, if sliding member 5 is moved to the right prongs 12 are withdrawn from socket portions 9 of post members 11 leaving that side unlocked and free to swing out of notches 8 for the addition or removal of loose leaf sheets. In this position the side of post members 11 containing socket portions 10 remains locked in place by the deeper penetration of said socket portions 10 by prongs 13. If sliding member 5 is moved to the left prongs 13 are withdrawn from socket portions 10 of post members 11 leaving that side unlocked. In this position the side of the post members containing socket portions 9 remains locked in place by the deeper penetration of said socket portions by the prongs 12.

To guide and limit the sliding motion of member 5 in member 4 a detent-like arrangement is provided by the cooperation of an upstruck button-like projection 14 of the channel member 4 with a centering hole 15 and slots 16 and 17 in the channel member 5. In addition slots 18 are cut in member 5 in which the shanks of rivets (not shown) are accommodated while the member 5 is being shifted to one side or the other. The slideable channel member 5 has upturned end flanges 19 to facilitate the transfer of the frictionally restrained channel member 5 by hand from its central position in the channel 4, in which the projection 14 of channel member 4 is held within the centering hole 15 of member 5, to a post member release position, in which projection 14 rides in either slot 16 or slot 17—the position chosen depending on which side of post member 11 requires freedom.

Reviewing briefly the operation, and considering particularly the assembled binder mechanism as shown in Figs. 2, 3 and 4, the post members 11 are released on one side or the other when the channel member 5 is moved within the guideway formed by channel member 4 by pressure on either of the flanges 19, so that the projection 14 rides out of the central hole 15 in channel member 5 against the frictional resistance offered by the bottom of channel member 5 until it drops

into either slot 16 or 17 as determined by the direction of the pressure applied to the flange member concerned. This motion of the channel member 5 is continued until either prong 12 or prong 13 of member 5 clears notch 8 in the side wall 6 of member 4. This frees one side of the post members 11 on one side so that loose leaf sheets may be added or removed. The action of returning the channel member to the central position locks the post members once more in sheet retaining position.

As shown in Figs. 4 and 5 the metal at the bottom of channel 4 is relieved on both sides of projection 14 by slots 20 to impart a spring-like quality to the strip 21 on which projection 14 is carried. So that, in effect, the projection 14 acts as a spring detent to locate the channel member 5.

Frequently loose-leaf post binders are used to contain records which are preferably locked in place after a period of use, so that, although reference may be made to the contents of said book, nothing may be added or removed without damage to the binder. Provision is made for this function in the improved structure of Figs. 2 to 10 by means of a locking tab 26 formed in the side 6 of the channel member by a U-shaped slot 27 cut therein, Fig. 3, and a rectangular opening 28, Fig. 9, cut in the side of channel member 5. When member 5 is in post member locking position, that is, centrally located in channel 4, as has been explained, the locking tab 26 coincides with the rectangular opening 28 so that, if the stiff tab 26 is bent into the opening 28 by force it will remain in this position by reason of the inherent inflexibility of the metal in small tab form used and so prevent any relative displacement of one channel member with respect to the other. There will be no easy way to bend the tab 26 back because the bound sheets will fill up and block off the inside of the U-shaped assembly.

The nearest prior art known to me is seen in Patent No. 1,876,232 of 1932. It will be seen on comparison that the structure of said patent is relatively cumbersome to make and assemble and entails a relatively high cost of manufacture. Analysis of the old and the new structure will show that the new one is a much simpler one for the user to understand and use. One purpose of the two structures is the same, that is "means whereby the fastening devices on both sides of a group of leaves may be concurrently operated and will release the leaf-securing members at either of their ends without, at the same time, releasing their other ends." This being so the new and useful structure of this invention disclosed is to be measured by the better way to accomplish the common purpose.

In the different structure, to accomplish the main purpose, there have been disclosed several structural features to make the binder more useful.

Having disclosed the invention, the claims are:

1. A loose leaf post binder comprising a channel member to be fastened on the inside of a binder case back panel, a second channel member cradled in the first one to slide back and forth, both sides of the first channel member having slots spaced along their upper edges, a set of posts, each having eyes at its opposite ends to rest in the said slots, both sides of said second channel member having spaced bayonet slots with their short portions opening through their upper edges, the slots being formed to straddle said eyes, the long portions of the bayonet slots on one side

being in reverse relation to those on the other side and all parallel and close to said upper edges of their channel member, all constructed and arranged so that prongs are provided above said long slot portions to fit the eyes of said posts and sliding of the second channel member in the first channel member to different positions may cause the prongs to engage the post eyes on one side while disengaging the eyes on the other side or oppositely engage and disengage them or engage the eyes of the posts on both sides.

2. A loose leaf post binder comprising a channel member to be fastened down on the back panel of a binder case, the upper edges of said member being turned inwardly and downwardly to form slides, a second channel member cradled to slide in the first one with its upper edge portions engaged in said slides, a set of posts each having eyes at its two ends, a set of short corresponding slots to pass the post eyes down or up for positioning or removing post ends with relation to corresponding top portions of both channel members, long slots closely adjacent to and parallel to the top edges of the second channel member and opening into its first named slots, the ones to pass the post eyes, the long slots on one side extending from its connected short slots in the opposite direction to that of the corresponding long slots on the other side, the material of the channel above the long slots being dimensioned to fit the eyes of said set of posts in the form of prongs, all constructed and arranged so that upon sliding the second channel member into balanced position with relation to the first member all the posts will be fastened in the binder in sheet retaining position, upon sliding to the right the posts will be released at corresponding ends on one side of the binder while being retained on the other side and upon sliding to the left the binder eyes will be released and retained respectively on their opposite sides.

3. The structure of claim 2 in combination with cooperating limiting means, part on one and part on the other of said channel members, to determine their functional positions of post retaining, post releasing on one side, and post releasing on the opposite side of the binder.

4. The structure of claim 2 in combination with a small opening through one side of the second channel member, a small tab to align with said small opening in the side of the first channel member when the two members are in balanced or sheet post retaining positions with prongs in all the eyes of all the posts, the metal of the channel members being adapted when the tab is bent into said small hole by a forcing tool to lock the binder parts for the prongs to retain all the posts in sheet retaining position against any normal attempt to release them.
